UNITED STATES PATENT OFFICE

117,196

DESIGN FOR AN ELECTRIC SHAVER

George T. Scharfenberg, Chicago, Ill., assignor to
Chicago Flexible Shaft Company, Chicago, Ill.,
a corporation of Illinois

Application July 28, 1939, Serial No. 86,283

Term of patent 14 years

To all whom it may concern:

Be it known that I, George T. Scharfenberg, a citizen of the United States, residing at Chicago, in the county of Cook and State of Illinois, have invented a new, original, and ornamental Design for an Electric Shaver, of which the following is a specification, reference being had to the accompanying drawing, forming part thereof.

In the drawing:

Figure 1 is a perspective view of an electric shaver showing my new design;

Figs. 2 and 3 are side views of the electric shaver taken at 90°, one with respect to the other;

Fig. 4 is a top plan view thereof; and

Fig. 5 is a diagrammatic section of the casing only on the section line 5—5 of Fig. 3.

In Figs. 1, 3 and 4, the face of the cutting head is shown diagrammatically.

I claim:

The ornamental design for an electric shaver, substantially as shown and described.

GEORGE T. SCHARFENBERG.
